VALVE

Lewis O. Gunderson and Oland W. Carrick, Chicago, Ill., assignors to Electro-Chemical Engineering Corporation, Chicago, Ill., a corporation of Delaware

Application October 20, 1937, Serial No. 170,031

16 Claims. (Cl. 137—103)

This invention relates to liquid actuated valves especially adapted for discharging impure boiler water and entrained solids from operating steam boilers without loss of steam from the boiler.

5 More specifically this invention relates to water actuated steam valves or traps adapted to rapidly and automatically discharge impure boiler water from operating steam boilers without loss of steam from the boiler.

10 In our copending application entitled: "Automatic boiler water conditioner and blow-off system", Serial 104,760, filed October 9, 1936, now Patent No. 2,132,028, granted Oct. 4, 1938, we have described and claimed an apparatus for collecting, directly from the main body of water in an operating steam boiler, boiler water that is above the normal level of water in the boiler and is contaminated with impurities such as foam forming ingredients and the like. This

15 collected water is drained from the boiler and may be utilized to actuate a blow-off valve for discharging sludge from the bottom of the boiler. We have now provided an automatically operating valve for use in apparatus such as is described and claimed in said application Serial 104,760, now Patent No. 2,132,028.

20 The valves of this invention include float chambers for receiving water collected from the top of the boiler water in an operating steam boiler to float an open topped bucket or container mounted in the chamber. The bucket will float in the chamber until the liquid in the chamber exceeds a predetermined level whereupon the liquid will flow into the bucket and sink the same to the bottom of the chamber. This floating and sinking of the bucket controls a small pilot valve which functions to effect the operation of two larger auxiliary valves communicating with a discharge port. One of the auxiliary valves joins the liquid inlet from the boiler directly with the discharge port while the other of said valves joins the float chamber with the discharge port, thus making possible a quick emptying of water from the bucket so that the same may again float in the float chamber and operate the pilot valve to close the auxiliary valves.

25 The water actuated valves of this invention thus only open to discharge liquid and will automatically close before steam from the boiler reaches the valve outlet.

An important feature of this invention includes a pair of opposed pistons slidably mounted 30 in an open ended cylinder formed in the dis-

charge port of the valve casing for opening and closing the auxiliary valves.

In one modification of the invention the bucket operated pilot valve opens and closes a bleeder passageway joining the space in the cylinder between the pistons with the float chamber so that when the bucket sinks to open the pilot valve this space between the pistons is subjected to boiler pressure and the pistons will, of course, be urged toward the ends of the cylinder to open 10 the auxiliary valves.

In another modification of the invention the space in the cylinder between the pistons is always in communication with the float chamber and the pistons are thus subjected to boiler pressure and are urged toward the ends of the cylinder to close the auxiliary valves. The bucket operated pilot valve functions to open and close a bleeder passageway joining the space in the cylinder between the pistons with the discharge 15 port so that when the bucket sinks in the float chamber to open the pilot valve, the boiler pressure in the space between the pistons is released and the auxiliary valves are forced open by pressure from within the boiler to rapidly discharge water in the float chamber and water 20 collected from the boiler.

It is then an object of this invention to provide a liquid actuated steam valve or trap for discharging impure water from operating boilers 25 without discharge of steam from the boiler.

A further object of this invention is to provide automatic water actuated valves for blowing down steam boilers.

A further object of this invention is to provide an automatic valve controlled by the floating and sinking of a water container in the valve.

Another object of this invention is to provide a valve with piston operated auxiliary valves controlled by a float operated pilot valve.

Another object of this invention is to provide a valve for automatically discharging impure boiler water from an operating steam boiler that cannot discharge steam from the boiler.

A further object of this invention is to provide an automatic valve for blowing down an operating steam boiler that is actuated by impure water collected from the top of the boiler water in the boiler.

Another object of this invention is to provide a steam trap having duplex auxiliary valves there-in controlled by a float operated pilot valve.

Other and further objects of this invention will become apparent to those skilled in the art from the following detailed description of the annexed

sheets of drawings which disclose two preferred embodiments of the invention.

On the drawings:

Figure 1 is a fragmentary diagrammatic side elevational view, with a part broken away and shown in cross section, of a locomotive boiler equipped with water actuated valves according to this invention, one of the preferred forms of valves being shown in solid lines and another preferred form of the valve being shown in dotted lines.

Figure 1—A is a fragmentary side elevational view of a by-pass piping arrangement for one of the water actuated valves shown in Figure 1.

Figure 2 is a vertical cross-sectional view, with parts in elevation, of a water actuated valve according to this invention.

Figure 2—A is a vertical cross-sectional view of a housing that can be used for the top portion of the valve shown in Figure 2.

Figure 3 is a vertical cross-sectional view, with parts in elevation, of another form of water actuated valve according to this invention.

Figure 4 is a vertical cross-sectional view, with parts in elevation, showing the valve illustrated in Figure 3 in open position.

As shown on the drawings:

The invention will be hereinafter specifically described as applied to a locomotive boiler but it should be understood that the valves of this invention have wide usage and are adapted to operate on all types of boilers.

In Figure 1, the reference numeral 10 designates generally a locomotive including the usual boiler shell 11, metal sheets 12 defining a firebox 13, steam outlet 14, steam dome 15, and engineer's cab 16.

As is described in our copending application Serial 104,760, a basin or collecting pan 17 is suspended from the boiler shell 11 and held rigidly in the steam space of the boiler between the steam outlet 14 and the primary evaporation zone of the boiler so that it will intercept any excessive foam development in the boiler that might otherwise continue towards the steam outlet 14 and be entrained with the steam. The basin 17 has the top edge thereof above the normal level of water in the boiler but below the level of foam or "concentrated" boiler water formed on top of the boiler water during operation of the boiler so as to receive this foam or concentrated water therein. The foam or concentrated water contains impurities dissolved and entrained therein that cause excessive foaming and inefficient operation of the boiler. A removal of these impurities is thus desirable.

In using one form of valve according to this invention a pipe 18 enters the boiler and extends through a side wall of the basin 17. A siphon leg 19 is secured to the end of the pipe 18 and extends downwardly toward the bottom of the basin 17. The pipe 18 drains the concentrated water from the basin 17 into a valve 20 according to this invention.

A blow-off valve 21 communicating with the lower portion of the boiler discharges into a pipe 22 communicating with the top of the valve 20. Concentrated water and sludge water entering the valve through pipes 18 and 22 are discharged through a discharge pipe 23 extending along the side of the locomotive as shown. The pipe 23 is secured to a T coupling 24 one leg of which receives a tube 25 extending into the cab 16 to operate a blow-off indicating gauge 26. The other leg of the T 24 receives a pipe 27 for con-

veying the concentrated water and sludge to a steam separator 28 mounted on top of the locomotive 10. Any steam that may have entered the discharge pipe 23 from the blow-off 21 or that may flash from the hot boiler water is separated from the water and escapes through an opening 29 to the atmosphere. The water and sludge is drained from the steam separator 28 through a pipe 30 extending to the bottom of the locomotive where it is discharged with harmless force along the road bed.

If it is desired to increase the rate of drainage of the concentrated water from the basin 17 without increasing the size of the valve 20, a by-pass arrangement such as is shown in Figure 1—A may be used. In this arrangement piping and couplings designated generally by the reference numeral 18a join the end of the pipe 18 with the end of the pipe 22 adjacent the valve 20. A check valve or one-way valve C is mounted in the piping 18a. The valve C only permits flow from 18a into the top of the valve 20 and automatically closes to prevent flow from pipe 22 into pipe 18. With this by-pass arrangement liquid from pipe 18 will actuate valve 20 to open the valve to discharge liquid into pipe 23. With the valve 20 open, liquid from pipe 18 can flow through the bottom of the valve 20 into the discharge line 23 as well as through 18a and through the top of the valve 20 with sludge from pipe 22 into the discharge line 23. Any desired proportioning of the amount of flow through the bottom of the valve 20 and through the piping 18a can be obtained by regulation of the size of the by-pass piping as well as the size of valve openings in the valve 20. Thus a small capacity valve 20 can take care of a rapid draining of the basin 17.

Structure of valve 20

The valve 20, as shown in Figure 2, comprises a casing composed of a bottom cup-shaped casting 31, a flat cover 32 for the bottom casting 31, and a top casting 33 secured on the cover 32.

The bottom casting 31 defines a cup-shaped float chamber 34 and has laterally extending flanges 35 on the back side thereof provided with holes 36 through the corners of the flanges for receiving bolts to secure the valve casing to the outside of the boiler shell 11 as shown in Figure 1.

In the central portion of the float chamber 34, the casting 31 has an upwardly extending lug 37 formed on the bottom wall of the casting for a purpose to be hereinafter described.

An inlet port 38 is formed through the top of the casting 31 for receiving the pipe 18 therein. The inlet port 38 communicates with the float chamber 34.

A drain plug 39 may be threaded through the bottom portion of the casting 31 for cleaning out the float chamber 34.

The cover member 32 is tightly secured on the member 31 at the top thereof and a gasket 40 may be interposed between the member 31 and the cover 32 for sealing the float chamber 34.

The cover member 32 has a downwardly extending leg 41 disposed in front of the inlet port 38 in spaced relation therefrom so that liquid from the pipe 18 will be deflected toward the bottom of the float chamber 34.

A threaded bore 42 extends through the central portion of the cover 32 for a purpose to be hereinafter described.

The top casting 33 is securely bolted on the cover 32 as by means of bolts 43 and is sealed on

the cover by means of a gasket 44 interposed between the member 33 and the cover 32.

5 The member 33 has an inlet port 45 at the top thereof for receiving the pipe 22 shown in Figure 1 and a discharge port 46 in the side thereof for receiving the pipe 23 as described in Figure 1.

10 The member 33 defines a discharge chamber 47 between the ports 45 and 46. An open ended cylinder 48 is formed integral with the member 33 in the discharge chamber 47. The open ends of the cylinder 48 are in alignment with the bore 42 through the cover member 32 and the inlet port 45 of the member 33 respectively.

15 Valve seats 49 and 50 are mounted in the discharge chamber 47 and are threaded respectively into the bore 42 of the cover 32 and the inlet port 45 of the member 33.

20 A pair of oppositely disposed pistons 51 and 52 are slidably mounted in the cylinder 48.

25 The pistons 51 and 52 have central apertures for receiving therethrough hollow plug members 53 and 54 which are threaded in auxiliary valves 55 and 56 to draw the valves against the pistons. Washers 57 can be interposed between the plugs 53 and 54 and the respective valves 55 and 56. The valve 55 is adapted to seat on the valve seat 49 while the valve 56 is adapted to seat on the valve seat 50.

30 The valve 55 has a passageway 58 through the central portion thereof while the valve 56 has a bleeder hole 59 cut therein communicating with a transverse passageway 60 joining the cylinder side of the valve with the discharge chamber 47. The mouth of the passageway 58 is beveled as at 59a to provide a seat for a needle valve head 61.

35 The space 62 in the cylinder 48 between the pistons 51 and 52 thus communicates through the passage 58 in the valve 55 with the float chamber 34 and when the needle valve 61 is unseated from the seat 59a, this space 62 also communicates through the bleeder passages 59 and 60 with discharge chamber 47.

40 The valve 61 has a hollow shank portion 61a receiving the end of a rod 62a therein. The opposite side walls of the shank portion 61a have elongated slots 63 therein and a wrist pin 64 disposed transversely through the end of the rod 62a extends into the slots 63 for loosely mounting the valve 61 on the end of the rod. The valve 61 thus has a limited longitudinal movement on the end of the rod 62a for a purpose to be hereinafter described.

45 The rod 62a extends from the valve 61 through the passage 58 of the valve 55 in spaced relation therefrom and into the float chamber 34 where it is secured at its other end in the bottom of an open topped container or bucket 65 mounted in the float chamber 34. Nuts 66 disposed on opposite sides of the bottom of the bucket 65 can be threaded on the end of the rod 62a for fixedly securing the rod to the bucket.

50 A hollow tube 67 is disposed around the rod 62a in the float chamber 34 in spaced relation therefrom and extends into the bucket 65. The top end of the tube 67 is threaded into the bore 42 of the cover member 32, so that the tube is rigidly suspended from the top of the float chamber 34. 55 A bearing member 68 is mounted in the tube 67 for slidably receiving the rod 62a therethrough to maintain the rod in the center of the tube. The bearing member 68 has passageways 69 therethrough permitting the passage of liquid 60 through the tube.

The bottom end of the tube is spaced from the bottom of the float chamber 34 so that the bucket 65 can float in liquid 70 introduced into the float chamber 34 through the inlet port 38.

65 A one-piece casting 33a (Fig. 2-A) can be used in place of the cover 32 and top casting 33 in the valve 20. The casting 33a has a rim portion 32a that takes the place of the cover 32. A boss (not shown) can be threaded in the mouth 45a of the casting 33a to receive the pipe 22. A wall W separates the space in the casting below the mouth 45a from the float chamber 34.

Operation of valve 20

70 The water 70 in the float chamber 34 floats the bucket 65 toward the top of the chamber to urge the needle valve 61 against the valve seat 59a. Since the space 62 in the cylinder 48 between the pistons 51 and 52 communicates with the float chamber 34, which chamber, in turn, is under boiler pressure since it communicates with the interior of the boiler through the pipe 18, the pistons are urged toward the ends of the cylinder 48 to seat the valves 55 and 56 on the valve seats 49 and 50. Under such conditions 75 the valve 20 is closed and neither sludge water from the blow-off 21 nor impure boiler water from the basin 17 can be discharged through the discharge pipe 23.

75 However when the impure boiler water in the basin 17 reaches a level above the top of the siphon leg 19, this water is siphoned off through the pipe 18 into the float chamber 34 and the level of water in the float chamber is raised above the top of the bucket 65. The water then rapidly fills 80 the bucket 65 and causes the same to sink to the bottom of the chamber 34 where it rests on top of the lug 37. The sinking of the bucket 65, however, causes the rod 62a to unseat the needle valve 61 and join the space 62 between the pistons with the discharge chamber 47 through the bleeder passageways 59 and 60. The pressure in the space 62 is thus reduced and since a relatively large area of the valves 55 and 56 are subjected to boiler pressure, these valves will move 85 into the cylinder 48 to be unseated from their seats 49 and 50 and thus join the float chamber 34 with the discharge chamber 47 as well as join the inlet port 45 with the discharge chamber 47.

90 Sludge water from the pipe 22 will thus be discharged into the discharge port 47 while impure water in the bucket 65 will be blown up through the tube 67 into the discharge chamber 47. Both streams of water are drained from the discharge chamber 47 through the discharge pipe 23.

95 The valves 55 and 56 will remain open as long as the bucket 65 is filled with water. However, as soon as the basin 17 is drained below the bottom of the siphon leg 19, the water supply to the float chamber 34 ceases and the bucket 65 will be rapidly emptied by the boiler pressure forcing water therein upwardly through the tube 67. As soon as the buoyancy of the bucket 65 is 100 reestablished by removal of water therefrom, the bucket will again float in the float chamber to seat the needle valve 61 against the valve seat 59a. Pressure in the space 62 between the pistons then immediately builds up to boiler pressure 105 and forces the valves 55 and 56 toward the ends of the cylinder 48 to seat the valves against the seats 49 and 50 and close the inlet 45 from the discharge chamber 47 as well as to close the float chamber 34 from the discharge chamber 47.

It is thus apparent that very little or no steam can reach the discharge chamber 47 since the valve 20 is actuated by water only.

The leg 41 of the cover member 32 prevents water entering the float chamber from flowing directly into the bucket 65.

The lost motion permitted by movement of the pin 64 in the elongated slot 63 of the needle valve shank 61a permits a small movement of the bucket 65 in the float chamber 34 without operating the valve. This is desirable to prevent the valve from being too sensitive, and furthermore insures a quick seating and unseating of the needle valve 61 since the bucket will already have been in motion before the pin 64 either pushes or pulls the needle valve 61 to seat or unseat the valve.

Construction of valve 80

20 In Figure 1 there is disclosed in dotted lines another form of valve 80 that can be used to replace the valve 20 described above. As shown in Figure 1, a pipe or tube 18' supplies the impure boiler water collected in the basin 17 to the top 25 of the valve 80. The valve discharges into a discharge pipe 23' on the outside of the boiler communicating with the pipe 21. In installations using a valve 80, no provision is made for the automatic blowing down of the lower portion of 30 the boiler since the valve 80 does not have a connection with the blow-off 21.

The flow of liquid through the discharge 23 or 23' is indicated to the engineer by the indicator 26. The indicator 26 in the engineer's cab shows 35 when the basin 17 is being drained.

As shown in Figures 3 and 4, the valve 80 comprises a two-piece casing including an open topped cup shaped member 81 having laterally extending flanges 82 on the back side thereof provided 40 with holes 83 through the corners of the flanges to permit bolting of the member 81 onto the outside of the boiler shell 11 as shown in Figure 1.

A drain plug 84 can be threaded through the bottom of the member 81.

45 The member 81 defines a float chamber 85.

A top member 86 is secured on the top portion of the member 81. The member 86 has an inner wall 87 extending from one side of the member 86 into spaced relation from the other side thereof and a similar bottom wall 88 in spaced relation from the wall 87. The walls 87 and 88 are connected by a cylindrical side wall 89.

The bottom wall 88 has a downturned lip or flange 90 extending into the chamber 85 of the member 81 in spaced relation from the side walls of the members 81 and 86.

The member 86 therefore has a compartment 91 therein communicating with the float chamber 85 and a separate compartment 92 separated from the float chamber 85.

A boss 93 is threaded through the top of the member 86 and receives in threaded relation therein the end of the pipe 18'.

The compartment 92 has an outlet port 94 therein receiving the end of the discharge pipe 23'.

The top wall of the compartment 92 has a valve seat 95 threaded therein for receiving the head 96 of a poppet valve 97. The stem 98 of the poppet valve 97 extends into the compartment 92.

The bottom wall 88 of the compartment has a boss 99 threaded therethrough and provided with a valve seat 100 for receiving the head 101 of a second poppet valve 102 having a stem 103 projecting into the compartment 92. The poppet

valves 97 and 102 thus open outwardly from the compartment 92.

An open ended cylinder 104 is mounted in the compartment 92 and formed integral with the side wall 89 of the compartment. The cylinder 104 has oppositely disposed pistons 105 and 106 loosely fitted therein.

The top casting 86 is thus identical with the casting 33a for the valve 20 except that in casting 86, the compartment 91 joins the end of pipe 18' 10 with the float chamber 85 whereas in casting 33a, there is provided the wall W dividing the compartment and preventing flow of liquid from the top to the bottom of the valve. The same pattern can thus be used for forming the top castings for both valves with a mere change in the cores used.

The stem 98 of the poppet valve 97 is secured to the piston 105 while the stem 103 of the poppet valve 102 is secured to the piston 106.

A space 107 is provided in the cylinder 104 between the pistons 105 and 106.

A passageway 108 extends through the head and stem of the poppet valve 102 and has a tapered mouth 109 formed on the valve head 101 to receive a needle valve head 110 in seating relation thereon.

The head 101 of the poppet valve 102 has a cylindrical extension 111 receiving the needle valve 110 therein.

A tube 112 is threaded into the boss 89 and extends into the float chamber 85. The cylindrical extension of the head 101 of the poppet valve is in slidably engagement with the interior of the tube 112 and the boss 89 and has a plurality of passageways such as 113 permitting flow of liquid between the extension 111 and the tube and boss. Alternatively the cylindrical extension 111 can be spaced from the tube and boss and have laterally extending fins or lugs in slid- 40 able engagement therewith.

The needle valve head 110 has a hollow shank portion 114 receiving loosely therein the end of a rod 115. The shank 114 of the valve head 110 has oppositely disposed elongated slots 116 there- 45 in for receiving the ends of a wrist pin 117 extending through the rod 115 whereby the valve head 110 is carried on the end 115 but can move longitudinally on the rod end within the limits 50 of the slots 116.

The rod 115 extends axially through the tube 112 and is secured at its bottom end to the bottom of a stamped metal container or bucket 118 mounted in the float chamber 85. For the purpose of uniting the bottom end of the rod 115 with the bucket 118 a nut 119 can be threaded into spaced relation from the end of the rod on the inside of the bucket 118. A rigidifying metal plate 120, also serving as a buoyancy adjusting weight, is mounted around the rod 115 beneath the nut 119 and the end of the rod extending beneath the bottom of the bucket 118 receives nuts 121 thereon to securely clamp the bottom of the bucket and the rigidifying plate between the nuts 119 and 121.

The tube 112 may have centrally apertured discs 122 secured therein or integral therewith in spaced relation along the length of the tube. Bushings 123 are carried in the discs 122 for slidably receiving the rod 115 in bearing relation therewith to maintain the rod in the center of the tube. The discs 122 have bores 124 there- 70 through to permit passage of liquid through the tube.

Operation of valve 80

Liquid in the float chamber 85 will float the bucket 118 and urge the needle valve head 110 against the seat 109 thus closing the passage 108 and separating the space 107 between the pistons 105 and 106 from the float chamber. Under such conditions the poppet valves 97 and 102 will be closed since the heads of these valves are subjected to boiler pressure existing in the inlet compartment 81 and the float chamber 85.

When impure boiler water collected in the basin 17 rises above the top of the siphon leg 19' this water will be siphoned out of the basin through the pipe 18' into the inlet compartment 81 of the valve 80 from which compartment it will flow into the float chamber thus eventually raising the liquid level in the float chamber above the top of the bucket 118. Liquid will then fill the bucket to destroy its buoyancy and cause the same to sink to the bottom of the float chamber as shown in Figure 4.

With a sinking of the bucket the rod 115 pulls the needle valve head away from the seat 109 and thus opens the passage 108 to place the space 107 between the pistons in communication with the float chamber. Since the float chamber is under boiler pressure the space 107 will likewise be under boiler pressure and this pressure exerted against the relatively large area of the heads of the pistons 105 and 106 will move the pistons toward the ends of the cylinder 104 thus unseating the poppet valve heads 96 and 101.

An opening of the poppet valve 97, as shown in Figure 4, joins the inlet chamber 81 with the discharge chamber 92 and liquid from the pipe 18' can directly flow into the discharge pipe 23'.

The opening of the poppet valve 102, as shown in Figure 4, joins the interior of the float chamber with the discharge chamber and liquid in the bucket 118 is blown by the boiler pressure up through the tube 112 into the discharge chamber for drainage through the discharge pipe 23'.

When the basin 17 is drained to a level below the bottom of the siphon leg 19' the liquid supply to the float chamber is cut off and the liquid in the bucket will be discharged through the tube 112 to substantially empty the bucket whereupon the same will again float to the top of the float chamber and seat the needle valve head 110. This seals the space 117 from the float chamber and cuts off the boiler pressure in the space. However the heads 101 and 96 of the poppet valves 102 and 97 respectively are still subjected to boiler pressure and are forced toward their seats. The liquid in the space 107 can bleed past the pistons 105 and 106 as shown in Figure 4 into the discharge chamber 92 thus permitting the pistons to slide into the cylinder 104. The boiler pressure thus closes the poppet valves 96 and 102 as soon as the liquid supply to the float chamber is cut off and before any appreciable amounts of steam can be discharged through the valves.

Summary

From the above descriptions it should be understood that the valves of this invention comprise casings defining float chambers for buckets or other floats adapted to float in liquid in the chamber until the liquid rises above a predetermined level, whereupon it will enter the buckets to sink the same.

The buckets control the operation of small needle or pilot valves which pilot valves, in turn, cause the function of two larger auxiliary valves. One of the auxiliary valves increases the rate of

discharge of liquid from the float chamber while the other auxiliary valve serves to communicate the liquid inlet of the valve directly with the liquid outlet.

The auxiliary valves are operated by opposed pistons slidably mounted in an open ended cylinder formed in the valve casing.

The valves of this invention quickly open in response to water or liquid flow and quickly close in response to the cessation of the water or liquid flow to prevent the discharge of steam through the valves. The valves efficiently accomplish the rapid discharge of liquid through a relatively small valve when the valve is open and at the same time the valves of this invention rapidly close upon the cessation of water flow to the valve.

The valve 20 can have a one-piece top casting such as 33a instead of the cover 32 and top casting 33. Likewise, the auxiliary valve and piston arrangement of valve 80 can be used in valve 20. Further, the auxiliary valve and piston arrangement of valve 20 can be used in valve 80.

The by-pass 18a shown in Figure 1-A on valve 20 can be used in systems where large amounts of water are collected in the basin 17 and where it is desired to have a high discharge rate for this water. The valve 80 itself has a high discharge capacity for liquid from basin 17 without having the liquid flow through the float chamber.

We are aware that many changes may be made and numerous details of construction may be varied through a wide range without departing from the principles of this invention, and we, therefore, do not purpose limiting the patent granted hereon otherwise than necessitated by the prior art.

We claim as our invention:

1. A liquid operated automatic valve comprising a housing having an inlet compartment and a discharge compartment, a pair of auxiliary valves separating said compartments, means defining a piston chamber in said housing, a pair of opposed pistons slidable in said chamber for operating said auxiliary valves, means defining a passageway joining the space in the piston chamber between the pistons with the inlet compartment, a bucket in said inlet compartment adapted to float therein and receive liquid therefrom and a pilot valve operated by said bucket for varying the pressure in the piston chamber between the pistons to slide the pistons and open the auxiliary valves thereby joining the inlet and outlet compartments.

2. A liquid operated automatic valve comprising a casing having a high pressure side and a low pressure side, an open ended cylinder in the low pressure side of the casing, a pair of oppositely disposed pistons slidably mounted in said cylinder, auxiliary valves operated by said pistons, an inlet port in said casing, one of said auxiliary valves separating the inlet port from the low pressure side of the casing, a float chamber in said casing adapted to receive liquid under pressure therein, the other of said auxiliary valves separating the float chamber from the low pressure side of the casing, said valve and its operating piston having a passageway therethrough joining the float chamber with the space in the cylinder between the pistons, a bucket adapted to float in the float chamber and receive liquid therein for sinking the bucket when the liquid level in the chamber increases beyond a predetermined amount and a pilot valve operated by said bucket to control the pressure in the cylinder.

space between the pistons for opening the auxiliary valves whenever the bucket sinks.

3. A valve adapted to discharge liquid from a boiler without discharge of steam which comprises a valve casing having an inlet compartment for communicating with the boiler to receive liquid therefrom and a discharge compartment, an auxiliary valve in the casing separating said compartments, means in said discharge compartment defining a piston chamber, a piston slideable in said chamber connected to said auxiliary valve for actuating said valve, means providing a passageway joining the inlet compartment with the piston chamber, a container in said inlet compartment adapted to float therein, said container receiving liquid therein to sink the container when said liquid reaches a predetermined level and a pilot valve operated by said container for controlling the pressure in said piston chamber whereby a sinking of the container effects an opening of the pilot valve thereby causing a change in pressure in the piston chamber to move the pistons for opening the auxiliary valve.

4. A valve comprising a casing having a float chamber, a liquid inlet and a liquid discharge opening, an open ended cylinder in said casing, a pair of oppositely disposed pistons slideable in the cylinder, a valve seat is spaced relation from each end of said cylinder, a valve carried by each piston for movement on and off of the valve seats, one of said valves separating the float chamber from the discharge opening and the other of said valves separating the inlet opening from the discharge opening, means defining a passageway joining the space in the cylinder between the pistons with the float chamber and a float operated pilot valve controlling the pressure in said space to operate said pistons.

5. A valve comprising a casing having an inlet compartment and an outlet compartment in the top portion thereof and a float chamber in the bottom portion thereof communicating with the inlet compartment, an open ended cylinder fixedly mounted in the outlet compartment, a pair of oppositely disposed pistons slideable in said cylinder, auxiliary valves connected to said pistons respectively separating the inlet compartment from the outlet compartment and the float chamber from the outlet compartment, a bucket in said float chamber adapted to float therein and receive liquid therefrom to sink the bucket when the liquid level in the float chamber exceeds a predetermined level and a pilot valve carried by the bucket for separating the space in the cylinder between the pistons from the float chamber whereby a sinking of the bucket opens the pilot valve, the space between the pistons is subjected to inlet pressure, the pistons are forced apart and the auxiliary valves are opened until the bucket again floats to close the pilot valve.

- 6.. A liquid actuated valve comprising a casing defining a float chamber, means giving entrance to the top portion of the casing, walls in said casing defining a separate compartment therein, valve seats in the top and bottom of said compartment, an open ended cylinder in said compartment, a pair of oppositely disposed pistons slideably mounted in said cylinder, poppet valves secured to said pistons having head portions adapted to seat on said valve seats, a passageway through one of said poppet valves joining the float chamber with the space between the pistons, a bucket mounted in said float chamber, a needle valve carried by said bucket adapted to close said passageway and a tube in said bucket extending

into spaced relation from the bottom thereof for conveying liquid from the bucket through the passageway to operate the piston for opening the poppet valves.

7. A liquid operated automatic valve comprising a two-piece housing composed of an open topped lower member defining a float chamber and an upper member having an inlet compartment and a discharge compartment, said inlet compartment communicating with the float chamber, means defining a vertical open ended cylinder in said discharge compartment, opposed pistons slidably mounted in said open ended cylinder, a poppet valve secured to the top piston for joining the inlet chamber with the discharge compartment, a second poppet valve secured to the bottom piston for joining the float chamber with the discharge compartment, said poppet valve secured to the bottom piston having a passageway therethrough communicating with the space between the pistons, a pilot valve in said float chamber adapted to close said passageway, a bucket in said float chamber adapted to float therein, a rod extending from the bottom of said bucket for carrying said pilot valve and an open ended tube surrounding said rod and extending into said bucket.

8. A liquid operated automatic valve comprising a casing having an inlet compartment, a float chamber for receiving liquid from the inlet compartment and a discharge chamber separated from the inlet compartment and float chamber, an open ended cylinder in said discharge compartment, pistons slideable in said cylinder, auxiliary valves operated by said pistons for joining the inlet compartment with the discharge chamber and for joining the float chamber with the discharge chamber, a bucket adapted to float in the float chamber and receive liquid from said chamber when the liquid exceeds a predetermined level, a tube extending axially into said bucket and a pilot valve carried by said bucket in said tube, said auxiliary valve joining the discharge compartment with the float chamber having a passageway therethrough communicating with the space between the pistons and a valve seat at the end of said passageway for receiving the pilot valve whereby a floating of the bucket seals the space between the pistons from the inlet chamber while a sinking of the bucket joins the space between the pistons with the float chamber for subjecting said space to inlet pressure to force the pistons apart and open the auxiliary valves.

9. A liquid operated automatic valve comprising a bottom casing member defining an open topped float chamber, a top casing member having an inlet compartment communicating with the float chamber and a discharge compartment separated from the inlet compartment and float chamber, valve seats in the top and bottom of the discharge compartment, an open ended cylinder in said discharge compartment, a pair of opposed pistons slideable in said cylinder, poppet valves carried by said pistons for operation on and off of said valve seats, means defining a passageway joining the space in the cylinder between the piston with the float chamber and a float operated pilot valve in said float chamber cooperating with the passageway for joining the space in the cylinder between the pistons with the float chamber when the float is at a predetermined level to subject said space to inlet pressures for forcing the pistons toward the ends of the cylinder to open the poppet valves.

10. A liquid operated automatic valve comprising

- ing a bottom casing member defining a float chamber, a top casing member secured to said bottom member and having an inlet and a discharge compartment therein, valve seats in the 5 top and bottom walls of said discharge compartment, an open ended cylinder in said discharge compartment, pistons loosely mounted in said cylinder for seepage of liquid between the pistons and the cylinder, auxiliary valves carried by said 10 pistons for operation on and off of said valve seats, means defining a passageway joining the space in the cylinder between the pistons with the float chamber, and a float operated pilot valve adapted to open and close said passageway.
11. A liquid operated automatic valve comprising 15 a float chamber adapted to receive liquid therein, an open topped container adapted to float in said float chamber, means defining a discharge compartment above said float chamber, an open ended cylinder in said discharge compartment, an inlet port at the top of said discharge compartment, a valve seat at the mouth of said port, a second valve seat in the bottom of said discharge compartment communicating with the 20 float chamber, auxiliary valves slidably mounted in said cylinder for operation on and off of said valve seats, means defining a passageway joining the space between the auxiliary valves with the float chamber, means defining a passageway 25 joining said space with the discharge chamber and a pilot valve carried by said open topped container for opening and closing said last mentioned passageway, thereby to cause opening and closing of said auxiliary valves.
12. A liquid operated automatic valve comprising 30 a bottom casing member defining a float chamber, an inlet port communicating with the float chamber for supplying liquid thereto, a bucket adapted to float in the float chamber, a tube extending from the top of said chamber into 35 said bucket, a top casing member defining a discharge chamber, an inlet port at the top of said chamber, a valve seat in the mouth of said inlet port, means defining a passageway joining the float chamber with the discharge chamber, a valve seat in said passageway, an open ended cylinder in said discharge chamber, auxiliary valves slidably mounted in said cylinder for operation on and off of said valve seats, a rod 40 carried by said bucket extending into the space between the auxiliary valves, means defining a bleeder passageway joining the space in the cylinder between the valves with the discharge chamber and a needle valve carried by said rod for 45 opening and closing said bleeder passageway.
13. A liquid operated automatic valve comprising 50 a casing member defining an open topped float chamber, an inlet port at the top of said casing member for supplying liquid to the float chamber, a cover member secured on top of said casing member having a bore therethrough and a downturned leg portion extending therein in front of said port, a top casing member secured on said cover having an inlet port at the top thereof and a discharge port at the side thereof, said top casing member defining a discharge compartment between said ports, a valve seat in said discharge compartment secured in the bore of said cover member, a second valve seat in said 55 discharge compartment secured in the mouth of said inlet port, an open ended cylinder in said discharge chamber, opposed pistons slidably mounted in said cylinder, an auxiliary valve se-
- cured to one of said pistons for operation on and off of the valve seat in the mouth of the inlet port, said valve having a bleeder passageway joining the space between the pistons with the discharge chamber, a second auxiliary valve secured to the other of said pistons for operation on and off of the valve seat secured in the bore of the cover member, said valve having a passageway joining the space between the pistons with the float chamber, a bucket in said float 60 chamber adapted to float and sink therein, a rod secured to the bottom of said bucket and extending into the space between the pistons, a needle valve head carried on the top end of said rod for opening and closing the bleeder passageway and an open ended tube secured in the bore of said cover member and extending into said bucket around said rod.
14. A liquid operated automatic valve comprising 65 a casing defining a float chamber, a bucket adapted to float in said chamber, an inlet port for said chamber, means defining a compartment above the float chamber, an inlet port and a discharge port for said compartment, a valve seat in said inlet port, said compartment having a passageway communicating with the float chamber, a valve seat in said passageway, auxiliary valves in said compartment operable on and off of said valve seats, a pilot valve carried by said bucket to actuate 70 said auxiliary valves, a by-pass joining the inlet port for the float chamber with the inlet port to the compartment and a check valve in said by-pass.
15. A liquid operated pressure valve comprising 75 a housing having two inlet ports subjected to pressure and an outlet port, a float chamber communicating with an inlet port, a float in said chamber adapted to rise and fall therein in response to variations in liquid level, independent 80 auxiliary valves separating each inlet port from the outlet port, independent pistons for operating each auxiliary valve, a single cylinder slidably housing both pistons, and means carried by said float to vent the space in the cylinder between 85 the pistons with an inlet port thereby utilizing the inlet pressure to force the pistons apart and open the auxiliary valves whenever said float moves to a predetermined position.
16. A high capacity liquid operated valve comprising 90 a housing defining a float chamber, a float adapted to rise and fall in said chamber, said housing having a plurality of pressure inlets and an outlet, at least one of said inlets communicating with the float chamber, auxiliary 95 valves separating the float chamber and each of said inlets from the outlet, pistons for actuating said auxiliary valves, means defining a passageway joining the float chamber with each piston, and a float-controlled pilot valve for controlling 100 the pressure on each piston whereby liquid collected in the float chamber will move the float to a predetermined position for actuating the pilot valve to change the pressure on the pistons and cause the pressure differential between the 105 inlets and outlet to open the auxiliary valves to discharge the liquid rapidly without necessity of moving all of the liquid through the float chamber and whereby said discharge will continue only as long as liquid in the float chamber maintains the predetermined position of the float.
